Inventor
THOMAS J. LITTLE JR

BY
J. King Harness

UNITED STATES PATENT OFFICE

THOMAS J. LITTLE, JR., OF DETROIT, MICHIGAN, ASSIGNOR TO COPELAND PRODUCTS, INC., OF DETROIT, MICHIGAN, A CORPORATION OF MICHIGAN

REFRIGERATOR

Application filed August 16, 1926. Serial No. 129,312.

An object of my invention is to provide refrigerating apparatus which may be so economically produced and assembled as to materially lessen the cost of mechanical refrigerators.

Another object of my invention is to provide refrigerating apparatus, the heat absorbing means of which may be utilized to partition the interior space of the refrigerator cabinet into separate compartments, and thereby utilize as little as possible of the food storage or freezing space in the cabinet.

A further object of my invention is to provide a refrigerating apparatus having a heat absorbing means which is in constant contact with all air strata of the interior space of the refrigerator cabinet, and to provide a heat dissipating means of the same construction as the heat absorbing means and which may be interchanged therewith.

A further object of my invention is to provide a unique assemblage of parts such as will make for economy, convenience and compactness.

With these and other objects in view, my invention consists in the arrangement, combination and construction of the various parts of my improved device, as described in the specification, claimed in my claims and shown in the accompanying drawings, in which:

Fig. 1 is a front elevation of a refrigerator cabinet with door removed showing my invention, partly in section, embodied therein.

Fig. 2 is a view taken on line 2—2 of Fig. 1. I have shown a refrigerator cabinet 1 having a motor 2 with a direct drive refrigerant compressor 3 secured thereto, positioned on the cabinet top 4. Within the storage space 5 of the cabinet 1 which is generally designated by the numeral 5, is positioned a refrigerant expansion chamber 6 of proper length, width and thickness to form a vertical partition dividing the storage space 5 into two separate compartments 7 and 8. The expansion chamber 6 is constructed of two sheets of metal imposed upon each other, and welded together at their edges as at 50, and at a plurality of indented points in their adjacent surfaces as at 51, thus forming enclosed connected spaces

between the welded points of the adjacent surfaces for containing refrigerant.

Secured to one side of the expansion chamber 6 at spaced intervals are a plurality of angle arms 9 for supporting containers or ice trays 13, and secured to the opposite side of expansion chamber 6 are a plurality of angle brackets 10 for supporting one side of the shelves 11. Similar angle brackets 10 are secured to the interior side wall of the cabinet 1 for supporting the opposite sides of shelves 11.

Beneath the lower edge of the expansion chamber 6 is positioned a drip pan 12 for receiving water formed by the melting of frost on the expansion chamber. A closure 14 is provided for the compartment 7 and has openings 15 therein for the insertion of the drawer-like ice trays or containers 13.

Vertically positioned upon and secured to the exterior back wall 16 (or to the side wall if desired) of the cabinet 1 by brackets 23 is a condenser 17 which is of the same form and construction as the expansion chamber 6, and as shown in the drawing, is of the same size.

The pipe 18 connects the compressor 3 with the condenser 17, the pipe 19 connects the condenser 17 with the expansion valve 20, the pipe 21 connects the expansion valve 20 with the expansion chamber 6, and the pipe 22 connects the expansion chamber 6 with the compressor 3, thus completing the refrigerant circulatory system.

In operation, the cooling action of the expansion chamber 6 upon the compartment 7 and the ice trays or food containers 13 is facilitated by the metal angle arms 9 which act as heat conductors or fins and add materially to the heat absorbing surface of the expansion chamber. The closure 14 which separates the compartment 7 from contact with outside air currents when the refrigerator cabinet is opened, and also from contact with air currents in compartment 8, makes it possible to maintain the low degree of temperature in compartment 7 which is necessary to the freezing of ice or of food preparations in the containers or trays 13. The angle brackets 10 which are secured to expansion chamber 6,

and the metal shelves 11 which rest thereon, may be heat conductors to increase the heat absorbing surface of the expansion chamber and facilitate the cooling action thereof, upon compartment 8. Those angle brackets 10 which are secured to the interior wall of cabinet 1 may be protected from heat conducting contact with the metal lining of the storage compartment 5 by interposing insulating material between the brackets and the metal lining.

It will be noted that the top 4 of the cabinet carries only the combined motor and compressor, so that considerable unused space is present. Extending from the free end of the motor 2, toward the front of the cabinet, is the motor shaft 52, the end of which may be provided with a taper and a key so that various household appliances may be fastened thereon, such as egg beaters, cream whippers, or any other piece of mechanism adapted to be rotated. Because of the large amount of unused space on the top of the box, it may be utilized as a table for such general work and the motor is accordingly positioned well toward the rear of the top.

Also, if desired, the bottom portion 55 of the closure or cover plate 14 may be made movable, as by hinging at 56, so that bottles of liquid or other like objects may be inserted through the same into the cooling chamber, when it is desired to cool them more quickly than would be possible in the food compartment.

It will be obvious that various changes may be made in the arrangement, combination and construction of the various parts of my improved device without departing from the spirit of my invention, and it is my intention to cover by my claims such changes as may be reasonably included within the scope thereof.

What I claim is:

1. In combination, a refrigerator cabinet having an expansion chamber therein, said expansion chamber comprising sheets of metal having refrigerant spaces between them, said sheets positioned to form a vertical partition dividing the cabinet into compartments of unequal size sealed against a substantial circulation of air between them, and a drip receiver positioned along the bottom edge of the partition.

2. In combination, a refrigerator cabinet having a storage space therein, a sheet-like refrigerant expansion chamber extending between the top and bottom thereof positioned within said storage space and dividing the same into separate compartments of materially different volumes, and ledges in thermal contact with said expansion chamber for combined heat absorbing fins and receptacle supports.

3. In combination, a refrigerator cabinet having a storage space therein, a vertically

extending refrigerant expansion chamber of substantially the same height as said space positioned therein and dividing the same into separate compartments of materially different volumes, a front cover plate for one of said compartments independent of the cover for said cabinet having a movable portion adjacent the bottom thereof whereby objects to be cooled may be inserted through the opening formed when such portion is opened and the portion moved back to maintain the closure.

4. In combination, a refrigerator cabinet having a vertically disposed expansion chamber therein, said expansion chamber comprising sheets of metal having refrigerant spaces between them, said sheets being positioned to provide a relatively imperforate vertical wall dividing the interior of said cabinet into a pair of chambers of materially different volumes.

5. In combination, a refrigerator cabinet adapted for artificial cooling and having a storage space therein, a refrigerating system having an expansion chamber of substantially the same height as said storage space vertically positioned within said storage space for dividing the same into separate compartments of materially different volumes, means in thermal contact with said chamber for supporting ice trays or food containers on the smallest compartment side of said expansion chamber, and means for supporting shelves on the other side of said expansion chamber.

6. In combination, a mechanically cooled refrigerator cabinet having a storage space therein, a primary closure for said space, a refrigerating system having an expansion chamber vertically positioned within said storage space for dividing the same into separate compartments of materially different volumes, means secured to the smallest compartment side of said expansion chamber serving as the sole support for ice trays or food containers, means on the other side of said expansion for supporting shelves, and a secondary closure for said smallest compartment.
